UNITED STATES PATENT OFFICE

JOSEPH C. DONNELLY, OF BARBERTON, OHIO, ASSIGNOR, BY MESNE ASSIGNMENTS, TO THE DIAMOND MATCH COMPANY, A CORPORATION OF MARYLAND

MATCH MACHINE

Application filed April 23, 1930, Serial No. 446,714. Renewed February 2, 1932.

- This invention relates to match making machines, and more particularly to that class of such machines wherein is employed an endless carrier adapted and arranged to receive succeeding transverse rows of splints at one location and transport them through the match making path to another location where the finished matches are punched row by row from the carrier.
- 10 A match making machine embodying my invention is especially, though not exclusively, designed for use in connection with the match packing machine forming the subject of an application for patent filed by me simultaneously herewith under Serial No. 446,715.
- The principal object of the present invention is the provision, in a match machine of the class mentioned, of coordinated carrier and punch actuating mechanisms whereby the rows of matches are discharged from the carrier with greater rapidity than the rows of splints are inserted therein, and whereby after each succeeding discharge of a prescribed number of rows of matches there is an idle period at the discharge station while the splint setting operation continues, thus permitting the efficient movement of a plurality of match receptacles into or from the match discharge path, throughout the width of the carrier, and this without curtailing the productive capacity of the match machine.
- The invention is herein illustrated as embodied in a match machine of the so-called "cut, set and dip" type wherein the splints are cut row by row from blocks of wood by vertically reciprocating cutters and inserted in succeeding rows of perforations in the plates of an endless carrier, but it is obvious that the invention may be embodied in the "set and dip" type of match machine wherein previously prepared splints are ejected row by row from a magazine and inserted in the perforations of the carrier plates.
- 45 A preferred embodiment of my invention will be hereinafter described, and the scope of the invention then be defined in the appended claims.
- In the drawings—
- 50 Figure 1 is a partial elevation of the delivery end of a match machine embodying the principle of my invention, showing an intermittently movable endless chain of receptacles adapted to receive the matches during the succeeding periods of discharge.
- 55 Fig. 2 is a similar elevation, on a larger scale, various parts being shown in section.
- Fig. 3 is a side elevation of the delivery end of the machine, showing in section the receptacle chain and its adjuncts, together with the block feed trough.
- 60 Fig. 4 is a transverse horizontal section of the machine directly above the pin wheels of the match carrier actuating mechanism, as on the line 4—4 of Fig. 3.
- 65 Fig. 5 is a similar section directly above the punch head at the match discharge station, as on the line 5—5 of Fig. 3.
- Fig. 6 is a transverse vertical section adjacent the variable pin wheel mechanism which determines the operation of the match carrier adjacent the punch head.
- 70 Fig. 7 is a sectional plan, as on the line 7—7 of Fig. 6.
- 75 Fig. 8 is a sectional plan of vibratory actuating arms for the timing pins of the variable pin wheel.
- Fig. 9 is a detail of a trip wheel, and adjuncts, for actuating the lifter for the said vibratory arms.
- 80 Referring to the drawings, 10 designates a part of the main frame of a continuous match machine, and 11 designates the main drive shaft.
- 85 12 designates a part of the match carrier comprising an endless chain of hingedly connected plates having parallel rows of perforations adapted to receive and hold match splints at one end and transport them through the match making cycle.
- 90 13 designates a vertically reciprocative setting head carrying a row of cutters 14 by means of which succeeding rows of splints are cut from blocks of wood and inserted in the perforations of the overlying horizontal run *a* of the match carrier.
- 95 15 designates the crank shaft for reciprocating the setting head, which shaft is appropriately geared with and driven from the main shaft.
- 100

16 designates a horizontally-reciprocative head carrying a row of punches 17 operative to eject the finished matches from the perforations of the vertical run *b* of the match carrier before its flexure at *c* to the horizontal path across the cutter head. The punch head is connected by parallel rods 18 to up-standing arms 19 fast on a rock-shaft 20 journaled in suitably-disposed bearings in the frame. 5 The rock-shaft 20 has also fast thereon an arm 21 which is connected by means of a rod 22 with an eccentric 23 on a lower cross-shaft 24 journaled in bearings in the lower portion of the frame. The shaft 24 is equipped with 10 a pinion 25 in mesh with a spur wheel 26 on the main shaft 11.

27 designates an endless conveyer having a succession of match receptacles 28 adapted and arranged to travel in a horizontal path 20 immediately below the plane of discharge of the matches from the match carrier and to receive the matches as they are delivered.

The mechanisms just referred to are or may be of any usual or approved construction, excepting as hereinafter particularly described.

Heretofore the match carrier has been uniformly moved intermittently at the splint inserting and match discharging stations, and 30 also the setting and punch heads have been reciprocated concurrently and at the same speed to effect respectively the insertion of splints in the carrier and the ejection of the finished matches.

35 In the present embodiment of my invention the punch head is operated at a higher speed than the setting head during the setting of a given number of rows of splints in the carrier, and the portion of the carrier adjacent 40 the punch head is moved at a correspondingly increased speed to present to the path of the accelerated punches a succession of rows of perforations equivalent to the series presented to the setting head, and is then 45 maintained at rest during the lagging interval of the setting operation, the punches 17 reciprocating idly in a row of perforations in the inactive portion of the carrier. In other words, in the setting of a series of rows 50 of splints, say, eleven rows, in one part of the carrier, a corresponding series of rows of finished matches are discharged from another part of the carrier in, say, one-half the splint setting period, such latter portion of 55 the carrier being quiescent during the remainder of the period and the punches reciprocating idly in a row of perforations.

A slackness of the match carrier at *c* in its travel between the match discharge and the 60 splint setting stations compensates for the speed difference of the carrier.

As illustrated, the horizontal and vertical portions of the carrier are relatively advanced across the setting head and in front 65 of the punch head by means of two pairs of

intermittently rotating gear wheels 29, 30, respectively, which mesh with adjacent marginal gear teeth 31 on the carrier plates. The two pairs of gears 29, 30 are fast on two suitably-disposed transverse shafts 32, 33, respectively, having their bearings in the main frame. In the present instance the shaft 33 is provided at one end with a gear 34 in mesh with an idler gear 35 which in turn meshes with a gear 36 fast on the shaft 32. The gear 34 is loose on the shaft 33 and has a bevel gear face 37 which meshes with a bevel gear 38 on an upright shaft 39, journaled in suitable bearing brackets 40 on the main frame. The lower end of the shaft 39 has fast thereon a pin wheel 41 whereof the pins 42 are engaged by a cam wheel 43 on a transverse shaft 44 which is operatively connected through gears 45 and 46 with the crank shaft 15. Thus continuous rotary motion is transmitted from the shaft 15 to the shaft 44 and its cam wheel 43. The contour of the cam surface and the spacing of the pins of the pin wheel 41 are such that the pins are successively engaged by the cam surface in a manner to effect a uniform intermittent rotation of the pin wheel and its shaft 39, thus correspondingly impelling the horizontal run of the match carrier through the transmission gearing described.

Previously the gear 34 has been fixed to the shaft 33 and therefore corresponding intermittent movements have been imparted to the horizontal and vertical runs of the match carrier through the agency of the single cam 43 and pin wheel 41 and the associated gearing, and the reciprocation of the punch head has been timed correspondingly with that of the setting head. According to the present invention the shaft 33 is operated independently of the cam 43 and pin wheel 41, to impart the series of high speed intermittent movements, with alternating prolonged dwells, to the carrier at the punch mechanism only, and the speed of the punch head is correspondingly increased as hereinbefore mentioned.

The preferred mechanism for operating the shaft 33 is as follows:

Loose on the end of the shaft 44 remote from the cam 43 is the elongated hub 47 of a cam wheel 48 which co-operates with the pins 49 of a second pin wheel 50 fast on the lower end of an upright shaft 51 having its bearings in brackets 52 on the adjacent side of the main frame. The acting surface of the cam 48 corresponds with that of the cam 43 and the spacing of the pins on the pin wheel 50 corresponds with that of the pins 42 of the pin wheel 41.

Fast on the cam hub 47 is a gear 53 which meshes with a gear 54 fast on the crank shaft 15, the ratio of the gearing, in the present instance, being such that the cam wheel 48

is rotated at twice the speed of the cam wheel 43.

On the upper end of the shaft 51 is a bevel gear 55 in mesh with a bevel gear 56 fast 5 on the adjacent end of the transverse shaft 33, and hence when the cam 48 is in operative engagement with the pin wheel 50 the portion of the carrier adjacent the punch head is intermittently moved twice as fast 10 as the portion of the carrier in the vicinity of the splint setting head.

Provision is had whereby when the pin wheel 50 has been intermittently rotated to effect the advancement of the carrier a distance of, say, eleven rows of matches, (during which period the portion, a , of the carrier in the vicinity of the setting head is advancing a distance of five and one-half rows of perforations) the next succeeding pin to 20 be engaged by the cam 48 is temporarily withdrawn from the path of the cam to permit the idle rotation of the latter during the advancement of the portion a of the carrier a distance of five and one-half rows of perforations, thus resulting in a prolonged dwell of 25 the carrier at the discharge station and permitting the idle reciprocations of the punches in the aligning row of holes in the carrier during its period of rest.

30 This done, the idle timing pin is returned to active position and the cam wheel 48 co-acting therewith again advances the pin wheel 50 step-by-step until another series of eleven matches have been discharged from 35 the carrier, whereupon the same or another suitably-located timing pin is moved to idle position, and so on.

In the present instance the pin wheel 50 is provided with twenty-one equally-spaced 40 pins, whereof two diametrically-opposite timing pins α are employed. Each of these pins is slidable in and projects above a perforated boss on the body of the pin wheel, and the upper end of the pin is jointed, as at 45 58, to the outer end of a vibratory radial arm 59. This arm is pivoted at its inner end, as at 60, to a suitable fixture 61 on the hub of the pin wheel. A spring 62 secured to the arm 59 and to the top of the pin wheel 50 maintains the arm normally depressed with the lower end of the pin extending into the active path of the cam surface. Projecting from the outer end of the arm 59 and beyond the periphery of the pin wheel is a toe 63 55 which at a proper interval of time in the rotation of the pin wheel 50 is brought above the path of a vertically-movable lifter 64, whereby when such lifter is raised or lowered it correspondingly raises or permits the 60 descent of the overlying radial arm, thus moving the timing pin out of or into the effective path of the cam.

The lifter preferably comprises a lever arm fast on one end of a shaft 640 having 65 its bearing in a bracket 65 in proximity to

the pin wheel 50. The other end of this shaft is provided with a depending toe 66 by actuation of which the shaft can be rocked and the lifter arm swung in a vertical arc. This toe, when the lifter arm is down, projects into the path of a semi-circular peripheral portion 67 of a trip wheel 68 fast on a shaft 69 which is mounted on the bracket 65 below the fulcrum of the lifter arm. Fast on the shaft 69 is a worm wheel 70 with 70 which meshes a worm 71 on the upper end of an inclined shaft 72. A bevel gear 73 on the lower end of the shaft 72 meshes with a similar gear 74 on the hub 47 of the cam 48, and hence during the rotation of the cam motion 75 is transmitted through the associated bevel and worm gearing to the shaft 69 in a manner to rotate the trip wheel in timed relation to the cam wheel 48, that is to say, during the succeeding step-by-step movements of the 80 pin wheel 50 the trip wheel is correspondingly moved step-by-step.

When in each rotation of the pin wheel 50 the toe 63 of one of the arms 59 is brought above the lifter arm, the leading end of the peripheral portion 67 of the trip wheel 68 impinges against the toe 66 of the lifter arm, thereby swinging the lifter upward and perforce raising the arm 59 and its associated pin α , thus rendering the pin wheel 90 inactive. The peripheral portion 67 retains the lifter raised and the pin wheel inactive until the trip wheel has made a semi-rotation, whereupon such portion escapes and releases the opposing toe 66, and the arms 64, 95 59 together with the timing pin resume their normal down positions. This done, the released pin is engaged by the cam 48 and the intermittent rotation of the pin wheel is resumed and continued until the leading end of the peripheral portion 100 67 of the trip wheel again engages the toe 66 of the lifter lever 64, whereupon the second timing pin is raised and the pin wheel 105 is rendered temporarily inactive, and so on throughout the match making cycle.

The ratio of the gearing for operating the punch head is such that the head and its punches are reciprocated in timed relation to the intermittent movement of the adjacent part of the match carrier. During the rapid active reciprocations of the punches in a succession of rows of perforations in the carrier the rows of matches thus ejected from the carrier are delivered to a series of the underlying receptacles 28, and in the interval of the idle reciprocations of the punches such receptacles are moved away from the carrier and another series of receptacles are positioned to receive the next succeeding 115 rows of matches discharged from the carrier, and so on.

In the present instance the punches are arranged in three spaced-apart groups or sections, as seen in Figs. 2 and 5, and hence the 120 125 130

matches are ejected in spaced groups. Consequently three properly spaced receptacles are positioned to receive the respective groups of matches during each period of 5 match discharge from the carrier.

The receptacles 28 preferably constitute temporary match holders which co-operate with match packing instrumentalities such as disclosed in my co-pending application 10 aforesaid. These holders are formed in spaced relation on the respective links of the endless conveyer 27 by means of cross-blades 75, each holder being transversely partitioned and occupying a space substantially equal in length to the interior of an ordinary match box tray. The conveyer is supported at its respective ends on suitable sprocket wheels 76, 77 (Fig. 1). This conveyer is intermittently actuated in timed relation to the match carrier to present a series of three temporary holders to the path of the matches discharged from the match machine during each succeeding dwell of the conveyer.

25. As a means to this end the shaft 78 of the sprocket wheel 76 remote from the match machine has fixed thereon a bevel gear 79 in mesh with a bevel gear 80 fast on a vertical shaft 81 journaled in a bearing on a suitable 30 supporting frame. On the lower end of the vertical shaft is a pin wheel 82 whereof the pins co-act with a cam 83 fast on a shaft 84 to which power is transmitted through suitable gearing from the main shaft of the match 35 machine. The contour of the cam surface and the ratio of the gearing are such that during each movement of the pin wheel the conveyer is advanced a distance of three temporary holders and temporarily locked at the end of 40 the step. As the conveyer intermittently progresses each succeeding series of filled holders are brought to a position where the contents of the holders can be removed and deposited in the match receiving elements of 45 a packing machine, for example.

It is to be understood that my invention is not limited to the particular exemplifying construction herein disclosed, as the mechanisms may be modified within the principle 50 of the invention and the scope of the appended claims.

I claim—

1. The combination with a match carrier, 55 splint setting mechanism at one location in the course of the carrier, match discharge mechanism at another location in said course, and means for moving the splint receiving portion of the carrier in timed relation to the setting mechanism whereby succeeding rows 60 of splints are inserted in the carrier, of means for actuating the discharge mechanism at a relatively higher speed than the setting mechanism, and means for actuating the carrier adjacent the discharge mechanism in timed 65 relation to the operation of the discharge

mechanism in such manner that after each succeeding discharge from the carrier of a plurality of rows of matches corresponding with a plurality of rows of splints inserted in the carrier in a given time by the setting head, the movement of the carrier adjacent the discharge mechanism is temporarily halted to compensate for the lag of the carrier at the setting head.

2. The combination with a match carrier, 70 a reciprocating splint setting head at one location in the course of the carrier, reciprocating match discharge punches at another location in said course, and means for moving step-by-step the receiving portion of the carrier in timed relation to the reciprocations of the setting head whereby succeeding rows of splints are inserted in the carrier, of means for reciprocating the punches at a relatively higher speed than the setting head, and means for imparting to the portion of the carrier adjacent the punches step-by-step movements in regular series alternating with prolonged dwells, each series corresponding in number 80 and distance with the movements of the carrier at the setting head, and each prolonged dwell being timed to compensate for the lag of the carrier at the setting head.

3. The combination with a match carrier, 85 splint setting mechanism at one location in the course of the carrier, match discharge mechanism at another location in said course, and means for moving the carrier at the setting head at a regular speed in timed relation to the setting mechanism, of means for actuating the discharge mechanism at a relatively higher speed than the setting mechanism, and means, including a co-operating cam and pin wheel, for actuating the carrier at and in 90 timed relation to the speed of the discharge mechanism, at least one of the pins being independently movable into and out of the active path of the cam, and means for rendering said pin active and inactive at predetermined intervals.

4. The combination with a match carrier, 95 splint setting mechanism at one location in the course of the carrier, match discharge mechanism at another location in said course, and means for moving the carrier at the setting head at a regular speed in timed relation to the setting mechanism, of means for actuating the discharge mechanism at a relatively higher speed than the setting mechanism, and means, including a co-operating cam and pin wheel, for actuating the carrier at and in 100 timed relation to the speed of the discharge mechanism, at least one of the pins being independently movable into and out of the active path of the cam, means for normally maintaining said pin in the active position, and means for rendering said pin temporarily inactive at predetermined intervals.

5. The combination with a match carrier, 105

- splint setting mechanism at one location in the course of the carrier, match discharge mechanism at another location in said course, and means, including a co-operating cam and a pin wheel, for actuating the carrier at the setting head, of means for actuating the discharge mechanism at a relatively higher speed than the setting mechanism, and means, including a second co-operating cam and a pin wheel, for actuating the carrier at and in timed relation to the speed of the discharge mechanism, at least one of the pins of the latter pin wheel being movable independently into and out of the active path of the cam, and means operative to render said pin active and inactive at predetermined intervals. 5 70
6. The combination with a match carrier, splint setting mechanism at one location in the course of the carrier, match discharge mechanism at another location in said course, and means for moving the carrier at the setting head at a regular speed in timed relation to the setting mechanism, of means for actuating the discharge mechanism at a relatively higher speed than the setting mechanism, and means, including a co-operating cam and a pin wheel, for actuating the carrier at and in timed relation to the speed of the discharge mechanism, at least one of the pins being independently movable into and out of the active path of the cam, means for normally maintaining said pin in the active position, pin-controlling means including a lifter operative to render the movable pin inactive at predetermined intervals, a rotary trip member for actuating said lifter, and means for rotating said trip member in timed relation to the cam. 15 75 80
7. The combination with a match carrier, splint setting mechanism at one location in the course of the carrier, and match discharge punches at another location in said course, of carrier actuating mechanism comprising two cams, means for rotating said cams at different relative speeds, pin wheels co-operating with the respective cams, the pin wheel which co-operates with the higher speed cam having at least one of its pins movable into and out of the path of the complementary cam, means for moving said pin into and out of active position at predetermined intervals, transmission mechanism between said pin wheels and the portions of the carrier adjacent the setting mechanism and discharge punches, respectively, and means for actuating said punches in timed relation to the speed of the adjacent portion of the carrier. 20 25 30 35 40 45 50 55 60 65 70 75 80 85 90 95 100 105 110 115 120 125 130
8. The combination with a match carrier, splint setting mechanism at one location in the course of the carrier, and match discharge mechanism at another location in said course, of means for moving the splint receiving portion of the carrier in timed relation to the setting mechanism whereby succeeding rows of splints are inserted in the carrier, means for actuating the discharge mechanism at a relatively higher speed than the setting mechanism, means for actuating the carrier adjacent the discharge mechanism in timed relation to the operation of the discharge mechanism in such manner that after each succeeding discharge from the carrier of a plurality of rows of matches corresponding with a plurality of rows of splints inserted in the carrier in a given time by the setting head, the movement of the carrier adjacent the discharge mechanism is temporarily halted to compensate for the lag of the carrier at the setting head, and means for intermittently advancing match receptacles in succeeding series to receive the matches discharged from the carrier, the movements of the receptacles being effected during the prolonged dwells of the carrier. 15 20 25 30 35 40 45 50 55 60 65 70 75 80 85 90 95 100 105 110 115 120 125 130
- Signed at Barberton in the county of Summit and State of Ohio this 21 day of April, A. D. 1930.
- JOSEPH C. DONNELLY.
